(57) **CLAIM**

The ornamental design for an electronic cigarette, as shown and described.

DESCRIPTION

FIG. 1 is a front, left-side perspective view of an electronic cigarette of the present disclosure;

FIG. 2 is a rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the encircled portion identified as 9 in FIG. 5;

FIG. 10 is an enlarged view of the encircled portion identified as 10 in FIG. 5;

FIG. 11 is an enlarged view of the encircled portion identified as 11 in FIG. 8; and,

FIG. 12 is an enlarged view of the encircled portion identified as 12 in FIG. 8.

The broken lines shown in the drawings represent portions of the electronic cigarette and form no part of the claimed design.
